ROLL SCREEN

Wilson P. Chamberlain, Jr. and Walter R. Hulberg, Corry, Pa., assignors to Corry Metal Corporation, Corry, Pa.

Application December 5, 1931, Serial No. 579,288

3 Claims. (Cl. 156—39)

This invention relates to screens, and more particularly to door and window screens of the roll type.

The primary object of the invention is the provision of a screen of this character which will roll within a housing conveniently located adjacent to the window or door opening with which the device is used, so that the screen will be fully protected when not in use.

10 An important object of the invention is to provide a screen of this character including guide strips arranged at opposite sides of the door or window opening, and so constructed that the edges of the screen and the lift rail forming a part thereof, will be held against lateral movement at all times thereby insuring the true winding of the wire mesh material of the screen, on its roller.

Another object of the invention is to provide a 20 device of this character wherein the contact felt thereof, is securely held within the lift rail of the screen, without the use of bolts, rivets or similar securing means.

A still further object of the invention is the provision of keepers that cooperate with sliding bolts of the lift rail of the screen, for holding the screen in its extended position, the keepers being removably supported at the ends of the guide rails and constructed in such a way that the lower 30 ends of the guide rails are closed by the keepers, which may be removed and replaced, should it become necessary to cut the guide rails to fit them within an opening.

With the foregoing and other objects in view, 35 which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

40 Figure 1 is an elevational view of a metallic screen constructed in accordance with the invention, parts thereof being shown in section.

Figure 2 is a sectional view taken on line 2—2 of Figure 1.

50 Figure 3 is a sectional view taken on line 3—3 of Figure 1.

Figure 4 is a sectional view taken on line 4—4 of Figure 1.

55 Figure 5 is a vertical sectional view through the lift rail and contact felt supported thereby.

Figure 6 is a perspective view of one of the removable guide members or shoes carried by the lift rail of the screen.

Figure 7 is a perspective view of one of the removable keepers.

Figure 8 is a sectional view through the modified form of lift rail guide and plaster jamb socket.

Referring to the drawings in detail, the reference character 5 designates the metallic window frame, within which the window screen, 65 forming the subject matter of the invention is positioned.

In the present showing, the housing in which the window screen is rolled, is mounted at the upper end of the window frame, however it is 70 to be understood that the housing may be supported at the sides or other convenient place, to meet various requirements of usage.

The housing which is indicated by the reference character 6, is of a length to extend between the side rails of a window or door frame, as clearly shown by Figure 1 of the drawings, the housing being rectangular in formation. The ends of the housing are closed by means of the end plates 7, that are so constructed that they fit 80 within the open ends of the housing, where they are bolted or otherwise secured in position.

The housing is formed with a longitudinal slot in the underside thereof through which the wire mesh material of which the screen is formed, 85 and to be hereinafter more fully described, passes into the housing.

These ends plates 7 are formed with depending flanges 8 that afford means whereby the housing may be secured in position between the 90 side rails of the window or door frame with which the device is used.

The roller on which the wire mesh material of the screen is wound, is indicated by the reference character 9, and is mounted in suitable 95 bearings mounted in the plates 7.

Secured to the side members of the window frame, are guide rails 26 which are formed by pressing a length of sheet metal material in such a way as to provide spaced walls 27 that have 100 longitudinal recessed portions 28 defining parallel ribs 29, the outer edges of the spaced walls being turned inwardly as at 30, providing a smooth surface for contact with the wire mesh material of the screen.

In the construction of these guide rails, longitudinal flanges 31 are provided, which flanges are provided with openings to receive securing screws to permit the guide rails to be secured in 105 position within a window frame.

110

The upper ends of these guide rails are open, the lower ends thereof being closed by means of the keepers 32 that are formed with end pieces 33 which contact with the lower ends of the guide rails closing the lower ends of the guide rails.

This construction permits of the ready removal of the keepers, should it be desired to cut the side rails in fitting the side rails within a window frame. The free end of the wire mesh material 17, is secured to the lift rail 34 by means of the spline 35 that fits within the clamp 36, which embodies a length of sheet metal material bent upon itself providing side members 37, which are held under the inturned ends 38 of the lift rail.

The construction of the lift rail is such that grooves 39 are formed in the outer surfaces thereof, providing ribs 40 that provide guides for the spring fingers 41 of the guide pieces or shoes 42, which are curved to fit within the ends of the lift rail, the curved walls of the lift rails and curvatures of the fingers insuring a close fit between the fingers and lift rail.

Should it be desirable to reverse the lift rail, to provide a clearance for sash hardware or other obstructions, this may be readily accomplished by removing the guide pieces 42 from the ends of the lift rail 34. The wire clamps 36 and spline 35, and wire 17, are now readily removed.

33 After the lift rail has been reversed, the wire cloth is positioned in the lift rail and the shoes or guide pieces are positioned in the ends of the lift rail.

These guide pieces 42 are formed with elongated heads 43 which when positioned within the guide rails, contact with the parallel ribs 29 to insure against lateral movement of the lift rail.

As clearly shown by Figure 8 of the drawings, 40 the lift rail comprises two lengths of sheet metal material bent to provide longitudinal groove 44 for the reception of the contact felt 45, one wall of the groove being formed with spurs 46 that are embedded in the felt to hold the felt in position within the groove of the lift rail. A flange 44' extends inwardly from the lift rail and is formed with an inturned flange 45' closely engaging the flange 46', of one of the lengths of sheet metal of the lift rail.

50 Thus it will be seen that due to this construction, the side members of the lift rail are held together without the use of rivets, bolts or similar securing means.

The lift rail 34 being hollow, provides a housing for the sliding bolts 47 that extend through openings in the guide pieces 42, where they project beyond the outer edges of the guide pieces and pass into the guide rails 26 for engagement with the keepers 32.

55 When the bolts 47 are in engagement with the keepers 32, the coiled spring 22 is held under

tension, to rewind the wire mesh material on the screen roller, when the sliding bolts are released or disengaged from the keepers.

The inner ends of the sliding bolts 47 are reduced to receive the springs 48 which have their inner ends positioned against the stop 49 that is secured within the lift rail, at a point intermediate the ends thereof. Secured to the sliding bolts 47 are finger pieces 50 that pass through openings in the lift rail, and extend to positions where they may be readily grasped by the operator to compress the springs 48 and retract the sliding bolts 47.

A modified form of guide to be used in conjunction with a plaster jamb socket is shown by Figure 14 of the drawings. The socket portion comprises a length of sheet metal material bent upon itself to provide spaced double walls defining a groove or guideway 51, to receive the extension 52 formed on the guide member 53. This form of guide rail and plaster jamb socket is especially adapted for application to plaster side jambs, and provides a yieldable connection between the extensions 52 and guideway 51. In this form of plaster jamb socket, lateral flanges 54 are provided, which flanges present flat surfaces to be embedded in the plaster of which the jamb is formed.

From the foregoing it will be seen that we have provided a metallic window screen which may be readily assembled or disassembled, the various elements of the screen being secured together by frictional contact, thereby eliminating the use of bolts, rivets, solder or other similar securing means commonly used in metallic screen construction.

Having thus described the invention what is claimed:

1. In a screen assembly having a screen member and a lift rail at one end thereof, guide rails having open ends, keepers within the open ends of the guide rails closing the lower ends of the guide rails and means carried by the lift rail and engaging the keepers for normally holding the lift rail and screen against movement.

2. A roll screen assembly including in combination, guide rails having grooves defining internal longitudinal ribs, a lift rail operating between the guide rails, guide pieces secured within the ends of the lift rail, said guide pieces having elongated heads, said heads of the guide pieces contacting with the ribs of the guide rails for guiding the lift rail.

3. A screen assembly comprising a lift rail, horizontally disposed longitudinal ribs within the lift rail, guide shoes having spring fingers fitted within the ends of the lift rail and contacting with the ribs to hold the shoes against movement, and guide rails in which the shoes operate.

WILSON P. CHAMBERLAIN, JR. 135
